United States Patent Office.

JOHN BOUSFIELD, OF CLEVELAND, OHIO.

Letters Patent No. 96,303, dated November 2, 1869.

MATCH-BOX.

The Schedule referred to in these Letters Patent and making part of the same.

To all whom it may concern:

Be it known that I, JOHN BOUSFIELD, of Cleveland, in the county of Cuyahoga, and State of Ohio, have invented certain new and useful Improvements in Match-Box or Holder; and I do hereby declare that the following is a full and complete description of the same, reference being had to the accompanying drawings, making a part of this specification, in which—

Figure 1 is a perspective view of the box and safe when used as a box.

Figure 2, a view of the same, when used as a match-safe.

Like letters of reference refer to like parts in the several views.

This invention relates to the construction of a box, the same to be used for the package and transportation of matches, and in which to keep them while being in use, as a safe.

This box is made of straw-board, or of any other material of a suitable nature, and which, in shape, is an oblong square, having the opening or top at A, fig. 1, the depth being equal to the length of a match, for the holding of which it is especially intended.

The cover of said box is made by the continuation of one of its sides beyond the height of the box, as shown at B, fig. 2, forming a kind of lappel, C, which,

on being turned down, covers the top, and which is secured in place by inserting the upper or circular part C between the inside of the box and its contents, as shown in fig. 1, the inserted end being indicated by the dotted lines a. The box, as thus used, forms a package of matches which may be boxed up in quantities for transportation.

On the front of the box or holder, or other convenient place, is a sanded or roughened surface, D, on which the match is rubbed to ignite it.

This box, when used as a match-safe, is opened as shown in fig. 2. The lappel or cover being raised, serves as a hanger, by which it may be hung against the wall by inserting the nail in the eyelet-hole b, thus obtaining a neat and perfectly secure match-safe at greatly less expense than those in ordinary use.

What I claim as my invention, and desire to secure by Letters Patent, is—

The box or holder described, provided with an adjustable lappel C, and sanded or roughened surface, being a new article of manufacture, substantially as and for the purposes set forth.

JOHN BOUSFIELD.
